UNITED STATES PATENT OFFICE.

WILLIAM T. BIESSEL, OF NEW YORK, N. Y., ASSIGNOR TO JOSEPH DIXON CRUCIBLE COMPANY, OF JERSEY CITY, NEW JERSEY, A CORPORATION OF NEW JERSEY.

PENCIL-DISPLAY BOX.

Application filed July 25, 1925. Serial No. 45,993.

The invention relates to an improvement in pencil display boxes.

The object of the invention is to so construct and arrange the parts of a pencil display box that the pencils therein will be displayed in a more attractive and attention-compelling manner than in the boxes heretofore provided for this purpose. To this end the invention consists in the improved pencil display box hereinafter fully described and particularly pointed out in the appended claims.

In the accompanying drawings illustrating the preferred form of the invention, Fig. 1 is a front elevation of the improved pencil display box, with the lower portion of the front of the box broken away, and with the pencils in the condition in which they are packed for shipping; Fig. 2 is a front elevation similar to Fig. 1, with the pencils in the condition in which they are displayed for sale on the counter or show case; Fig. 3 is a transverse section, on an enlarged scale, through the box, with the hinge or easel in closed condition; Fig. 4 is a view similar to Fig. 3, with the hinge or easel in open condition and showing the method employed for raising the middle section of the pencils; Fig. 5 is a section taken along the line 5-5 of Fig. 6; and Fig. 6 is a section through the lower left hand corner of the box, with the pencils removed.

The improved pencil display box, as illustrated in the drawings, is an elongated structure open at its upper side and adapted to hold a row or rows of pencils 9 in upright position. In form the box is rectangular and comprises a rear wall 10 which is continuous throughout the length and depth of the box and a front wall 11 having the middle open space 12 and the upper open space 13, the open spaces 12 and 13 being separated by the longitudinal band 14. The lower portion of the front wall 11 and the band 14 are adapted to present the usual advertising matter of the manufacturer and seller of pencils. The lower end of the box is closed by a bottom which consists of a flange 15 projecting forwardly from the lower end of the rear wall 10 and a flange 16 which projects rearwardly from the lower end of the front wall 11. Each end of the box is closed by a wall consisting of a flange 18 projecting forwardly from the rear wall and a flange 19 which projects

rearwardly from the front wall 11. These parts may be secured together by glue and by rivets. The surfaces of the front, rear and side walls of the box exposed to view, as well as the bottom of the box, are covered by a good quality of glazed paper or the like indicated at 20. The body portion of the box constituted by the front, rear, side and bottom walls may be composed of any material suitable for the purpose, such as card- or paste-board.

The box may be made in such proportions as to hold any desired number of pencils. A box of convenient size will hold and fully display one-half a gross of pencils arranged across the box in two rows of thirty-six pencils each. In order that the display box may be used for an assortment of pencils of different grades, and especially of differently colored pencils, the box is provided with a series of open faced compartments, each compartment being arranged to hold twelve pencils of the same quality or colored alike. Each pencil holding or segregating compartment comprises a rear wall 22 and two end walls 24. The walls of the compartments terminate at their upper ends 25 behind the longitudinal band 14 and at their lower ends 26 behind the upper part of the lower section of the front wall 11. The rear walls 22 of the pencil compartments are secured to the inner face of the rear wall 10 of the box. The outer side walls of the two end compartments are embraced by the inturned ends 27 of the flanges 18 of the rear wall 10, which arrangement lends strength to the construction. The exposed front edges 28 of the abutting side walls of the adjacent compartments are preferably covered with a material of the same character as the covering 20.

When the pencils are placed in the box with the pencils of the same grade or like exterior color segregated in their appropriate compartments, the box of pencils has the appearance shown in Fig. 1. In this condition the box may be shipped or otherwise handled. When, however, the box is placed on the counter, show-case or other support for displaying the pencils for sale, the rows of pencils in the box are caused to assume the positions shown in Fig. 2. It will be observed that the rows of pencils slope gradually in two pleasing curves from their middle section to the two ends of the

box, thereby displaying the pencils in a most attractive manner. If the pencils in the different compartments are differently colored it will be understood that this will add to the attractiveness of the display and thereby invite and even compel the attention of the purchaser.

The means for causing the rows of pencils in the box to rise highest at their middle section and to slope gradually in a pleasing curve toward each end of the box consists of a flexible pencil support 30 which may conveniently be a strip of fibre-board or some similar flexible material. When the box is in the condition shown in Fig. 1, the weight of the pencils in the box depresses and holds the support 30 against the in-turned flange 15 of the rear wall 10. Each end 31 of the support 30 is upturned and secured between the lower end of the flange 18 of the rear wall 10 and its in-turned lip 27, as clearly shown in Fig. 6. It will be understood that by raising or lifting the middle of the flexible support 30, the ends of the support being held fast, the rows of pencils will assume the position shown in Fig. 2, the flexibility of the support being such that the weight of the pencils causes the support to bend or curve in the manner shown. In order that the middle portion of the pencil support may be raised sufficiently high for the pencil display purpose, the lower ends 32 of the in-turned lips 27 of the flanges 18 terminate above the flange 15, as shown more clearly in Fig. 6.

Although any preferred means may be employed for raising or lifting the middle of the flexible pencil support 30 to display the upper ends of the pencils in the manner shown in Fig. 2, it is preferred to employ the usual hinge or easel 34 for this purpose, so that when the box is placed in position for display purposes and the hinge 34 is swung rearwardly from the box to hold it in position, as shown in Fig. 4, the support 30 and pencils will be thereby raised without any further or other attention on the part of the user. For this purpose a flexible strip or tape 35 preferably composed of textile fabric is used, the front end 36 of the tape passing under the middle of the support 30 and the rear end 37 of the tape being secured to the hinge 34. The forward extremity 38 of the tape 35 passes through a slit in the upper edge of the lower section of the front wall 11 of the box and is turned down, being secured in position between the front wall 11 and the covering 20. The rear end 37 of the tape 35 is downturned and is secured against the rear surface of the hinge 34 by a covering 39. The point 40 at which the tape 35 is secured in the front wall 11 and the point 41 at which the tape passes through the rear wall 10 of the box are substantially on a line. The height of

the points 40 and 41 above the bottom of the box depends on how high it is desired to raise the middle of the rows of pencils. The point 42 at which the tape 35 is secured to the hinge 34 is but slightly below the plane of the points 40 and 41 in the form of box shown in the drawings and may be on the same plane or slightly above it. By observing the position of the parts shown in Fig. 3, it will be understood that when the hinge 34 is swung rearwardly, as shown in Fig. 4, the tendency of the tape 35 to assume a straight line causes the middle of the flexible support 30 to be raised, and so display the tops of the pencils in the curved lines shown in Fig. 2.

The hinge 34 may be of any preferred width and its downturned upper end 44 is secured to the upper end of the middle part of the rear wall 10 to form the pivot point 45 which is covered over by the part 46 of the covering 20. When the hinge 34 is swung rearwardly to support the box in display position, the hinge is held in open position by means of a brace 47 integral at its lower end 48 with the lower end of the hinge 34, the flexibility of the material of which the hinge is composed permitting the hinge and brace 47 to be folded upon themselves, as shown in Fig. 3. The inner end 49 of the brace 47 is adapted to bear against the rear surface of the wall 10 to thereby hold the hinge 34 in braced position. The brace 47 is provided with the slot 50 to accommodate the tape 35.

Although the invention has been described as especially adapted for displaying pencils, it will be understood that it is not to be restricted to this purpose, since it is equally well adapted to display other articles.

Having thus described the invention what I claim as new is:

1. A pencil display box comprising, a rectangular structure open at its upper side adapted to contain pencils and the like in upright position, a flexible strip located under the pencils, a tape secured at its front end to the front of the box and passing under the middle of the flexible strip, and means for acting on the tape to raise the middle portion of the strip.

2. A pencil display box comprising, a rectangular structure open at its upper side for containing pencils and the like in upright position, a strip of flexible material located under the lower ends of the pencils and upon which the pencils are adapted to rest, means for securing the ends of the strip to the box, a tape located under the middle of the flexible strip, said tape being secured at one end to one wall of the box and passing through a hole in the opposite wall of the box at a point opposite to the point at which it is secured to the first wall, and means by which the free end of the tape may be pulled to

raise the middle portion of the flexible strip.

3. A display box comprising, an elongated structure open at its upper side adapted to contain a row of pencils or the like in upright position, the tops of said row of pencils being in a plane substantially parallel with the longitudinal axis of the box, raisable means for supporting the pencils in display position so that the middle section of the row of pencils will be higher than the end sections, and means for holding the pencil supporting means in display position.

4. A display box comprising, an elongated structure open at its upper side adapted to contain a row of pencils or the like in upright position, flexible supporting means secured at its ends to the box and located under the pencils, and means located under the middle portion of the flexible supporting means for acting thereon so that the middle section of the row of pencils will be higher than the end sections.

5. A display box for pencils and the like comprising, an elongated rectangular structure open at its upper side and having front and rear walls, a strip of flexible material located in the bottom of the box under the pencils and secured at its ends to the box, a flexible tape secured at one end to the front wall of the box at a point above the bottom of the box, said tape passing down by one side of the lower ends of the pencils, under the strip, up by the other side of the lower ends of the pencils and out through a hole in the rear wall of the box at a point substantially opposite the point where the tape is secured to the front wall, and a hinge for supporting the box in display position, the other end of the tape being secured to the hinge, the arrangement being such that when the hinge is swung outwardly from the box the tape raises the middle portion of the flexible pencil supporting strip.

WILLIAM T. BIESEL.
